Primary Examiner — Barbara Fox*Assistant Examiner* — Jessie Anne E Touart(74) *Attorney, Agent, or Firm* — Jonathan A. Bay(57) **CLAIM**

The ornamental design for an archery arm guard, as shown and described.

DESCRIPTION

FIG. 1 is a perspective view of an archery arm guard showing my new design shown in an environment of use; FIG. 2 is an enlarged-scale perspective view of detail 2-2 in FIG. 1;

FIG. 3 is an obverse elevational view shown removed from environment for clarity;

FIG. 4 is the opposite elevational view thereof;

FIG. 5 is an outboard side elevational view thereof;

FIG. 6 is an inboard side elevational view thereof;

FIG. 7 is a top plan view thereof; and,

FIG. 8 is a bottom plan view thereof.

The broken lines in FIGS. 1 and 2 represent environmental subject matter that forms no part of the claimed design. The dash-dot-dot-dash broken lines in FIG. 1 indicate cutoff boundaries for enlarged portion views and form no part of the claimed design. The broken lines in FIG. 4 depict portions of the archery arm guard that form no part of the claimed design.
